OIL BURNER

Filed Oct. 22, 1926

UNITED STATES PATENT OFFICE

HENRY DITTES, OF MINNEAPOLIS, MINNESOTA

OIL BURNER

Application filed October 22, 1926. Serial No. 143,335.

My invention relates to oil burners and has for its object to provide an oil burner including a nozzle furnished with pre-heated air, liquid fuel, and steam.

5 Another object of the invention resides in heating the fuel prior to the introduction of the same into the nozzle by means of the heated air as well as the steam.

A still further object resides in providing a horizontal pipe leading up to the nozzle and connected with an air preheater and in positioning within said pipe a second pipe connected with a source of liquid fuel and positioning within said second pipe a 15 third pipe connected with a steam generator, all of said pipes leading up to said nozzle.

A still further object of the invention consists in providing a toroidal air preheater 20 within the fire pot of the heating plant in which the oil burner is installed, said preheater lying along the inner surface of the fire pot of said heating plant, and being connected at one end with said outer pipe 25 leading to the burner nozzle and being constructed in detachable sections.

A still further object of the invention resides in arranging the nozzle concentrically relative to said preheater and in positioning within said preheater and encircling said nozzle a spiral coil for generating steam, said coil being connected with said steam pipe.

A feature of the invention resides in arranging the convolutions of said steam coil in inverted conical formation, and in positioning said nozzle below the upper level thereof, said nozzle being provided with an inverted conical deflector for directing 40 the flame from the burner along said steam coil and preheater.

An object of the invention resides in forming said nozzle with three concentric vertical pipes situated one within the other, the 45 ends of said pipes being progressively arranged below the ends of the surrounding pipe to provide jets, said pipes being connected to said aforementioned pipes and furnished with air, fuel and steam, respectively.

Another object of the invention resides in providing baffles within said outer and intermediate pipes above the ends of said intermediate and inner pipes for assisting in vaporizing the fuel directed into the nozzle.

With the foregoing and other objects in view, which will appear in the following description, the invention resides in the novel combination and arrangement of parts and in the details of construction herein-after described and claimed.

In the drawings illustrating my invention:

Fig. 1 is an elevational view of a heating plant with a portion thereof drawn in section and illustrating the application of my improved oil burner thereto.

Fig. 2 is a plan sectional view taken on line 2—2 of Fig. 1.

Fig. 3 is an enlarged longitudinal sectional view taken through the center of my improved burner nozzle.

Fig. 4 is an enlarged sectional view of a portion of the preheater used with my invention.

For the purpose of illustrating the application of my improved oil burner, I have shown in the drawings a heating plant indicated in its entirety at A, which may be either a boiler or hot air furnace, or any other form of heating plant, as desired. This heating plant is constructed with the usual sections forming a fire pot 10 and an ash pit 11, said sections being arranged with an ash pit opening 12 and a coal opening 13. Inasmuch as the particular type of heater in which the invention may be installed does not form any particular feature of the invention, the same has only been shown generally without illustrating the specific construction thereof.

The oil burner proper, which is indicated in its entirety at B, is principally positioned within the fire pot 10 and has certain portions thereof extending down into the ash pit 11 and through the ash pit opening 12. This burner comprises primarily a nozzle 14 connected with a preheater 15 and a steam generator 16 as well as to a suitable source of supply for liquid fuel.

The nozzle 14 is shown in detail in Fig. 3, and consists of an outer pipe 17 centrally disposed within the fire pot 10 in vertical position. Within this pipe is concentrically arranged an intermediate pipe 18, the upper end 19 of which is disposed considerably below the upper end 20 of the pipe 17. Between the two ends 19 and 20 of pipes 18 and 17, and within the pipe 17 is arranged 5 a cage 21 supporting a plurality of baffles 22 arranged to deflect and agitate the fuel mixture ejected from the nozzle. Within the pipe 18 is concentrically arranged an inner pipe 23 having its upper end 24 disposed below the upper end 19 of said pipe 18 to provide a steam jet. A cage 25 similar to the cage 21 and having a plurality of baffles 26 formed therein is positioned between the ends 19 and 24 of pipes 18 and 20 15 23 within the upper portion of said pipe 18. These baffles, as well as the baffles 22, serve to atomize and break up the fuel globules in a manner to be presently explained. At the top of the pipe 17 is arranged a spider 25 59 which is formed with a boss 60 tapped to receive a threaded spindle 61 attached to a conical deflector 57. This deflector serves to throw the flame from the nozzle outwardly along the steam generator 16 and 30 the preheater 15, as well as toward the walls of the interior of the fire pot or combustion chamber 10. By turning the deflector 57 through the agency of a hexagonal head 62 formed thereon, the distance between the 35 upper end 20 and the walls of said deflector may be varied at will so as to regulate the formation and condition of the flame.

In the installation of the oil burner the grates are preferably removed, and a funnel shaped plate 27 inserted within the fire pot 10 immediately above the ash pit 11. This plate is formed with an outwardly extending flange 28 which may be made separate therefrom and supported thereon in any 40 45 suitable manner. For permitting the insertion of this structure into the fire pot, the same may be made in sections so that it can be inserted through the ash pit opening 12 or the coal opening 13 and subsequently 50 bolted together after being arranged in place within the fire pot 10. The manner of constructing these plates being obvious, the same has not been illustrated in detail in the drawings. The nozzle 14, as shown in 55 Fig. 1, is centrally disposed within the fire pot 10 and extends upwardly through the apex of the funnel shaped plate 27, and carries a collar 29 which serves to support plates 27 and 28 in place within the heating 60 plant.

The preheater 15 which is for the purpose of heating the air before the same is mixed with the liquid fuel is constructed as best shown in Figs. 2 and 4, and consists of a 65 plurality of arcuate tubular sections 30

formed with socketed ends 31 adapted to be bolted together by means of bolts 32. The bolts 32 are positioned above and below the said sections and pass through lugs 33 formed thereon. The socketed ends of said sections are of spherical formation so that the same may rock a slight amount permitting the adjustment of the entire assemblage of sections to conform to the curvature of the interior of the fire pot proper. By means of this construction the preheater 15 may be made to fit any of the different sizes of fire pots now in common use for residential types of boilers and furnaces by selecting the proper number of sections and attaching the same together in the desired angular relation to one another. In addition to the intermediate sections 30, I employ two end sections 34 and 35 constructed in the form of elbows, which extend downwardly through the flange 28 on plate 27. The end section 34 serves as an inlet for the preheater 15 and draws fresh air from the ash pit 11 which enters the same through the opening 12. The other section 35 of the preheater serves as an outlet and is connected with a depending pipe 36 which extends down into the ash pit 11. This pipe is connected to a horizontal pipe 37 by means of an elbow 38. Pipe 37 projects outwardly through the opening 12 of the heating plant, as best shown in Figs. 1 and 2. A second pipe 42 runs adjacent the pipe 37 and is connected at one end to said horizontal pipe by means of a reducing T 39 and an elbow 40, and is connected at its other end to the pipe 17 of nozzle 14, by means of an elbow 41. This pipe serves to furnish heated air to the nozzle for mixture with the fuel vapor in a manner to be presently described.

Within the horizontal pipe 42 is arranged an intermediate pipe 43 which is secured in the reducing T 39 and runs concentrically within said horizontal pipe. Pipe 43 is connected to the intermediate pipe 18 of nozzle 14. In said pipe is positioned a T 45, which in turn, is connected to a supply pipe 46 leading to the supply tank for furnishing liquid fuel to the burner. The said pipe 43 terminates in a reducing coupling 47 which has secured in it an inner pipe 48 extending within said pipe 43 in spaced relation to the walls thereof, which inner pipe is connected to the inner pipe 23 of nozzle 14 the same as pipe 43 is connected to pipe 18. A valve 44 is connected in the pipe 46.

The steam generator 16 consists of a coil of pipe arranged with a number of spiral convolutions 49 which are arranged in the form of an inverted cone, said convolutions being positioned within the toroidal preheater 15 and encircling the nozzle 14. The upper end 50 of this heating coil is con-

nected by means of a union 63 and a pipe 51 to the pipe 48 previously referred to. The lower end of this pipe indicated at 52 is similarly connected by means of a union 64 to a supply pipe 53; which in turn is connected to any suitable supply line furnishing water under pressure to the generator. A regulating valve 54 is positioned in this pipe in proximity to the regulating valve 44 and serves to control the water entering the steam generator. If desired the valve stems of these two valves may be connected together by means of a single control lever 55 so that the two valves may be simultaneously operated. It will hence be readily seen that the amount of steam generated is proportional to the opening of the valve 54 and that the quantity of steam injected into the burner will be in proportion to the amount of fuel entering the same. If so desired a manually controlled valve 69 may be inserted in the air pipe 37 for regulating the volume of air entering the burner.

The entire burner including the plates 27 and 28 which are carried on the pipe 17 are all supported upon a standard 56 located within the fire pot 11 and beneath the various pipes of the burner. In addition the pipes connecting the fuel reservoir and the water supply system with the burner serve to further stiffen and support the structure. It can, however, readily be comprehended that the burner may be supported in any desired suitable manner.

In the use of the burner the operation is as follows. In starting the burner, gasoline, alcohol, or some other suitable priming fuel is poured into the funnel shaped member 27 surrounding the nozzle 14. Upon igniting this fuel the steam coil 16 and the preheater 15 as well as the nozzle 14 are all heated so that when the valves 44 and 54 are opened by means of the lever 55, fuel and water are supplied to the burner. The water upon entering the heated coil 16 immediately turns into steam and the steam passing through the pipe 23 causes a suction in the pipe 18 drawing the fuel from the same and discharging the fuel through the pipe 18.

The fuel is preferably maintained at a level approximately at the upper end 24 of pipe 23 by proper float mechanism not shown in the drawings so that the same is always available to be picked up by the live steam issuing from the pipe 23. The mixture of steam and fuel vapor leaving pipe 18 creates a suction in pipe 17 which draws heated air through the preheater 15 from the ash pit 11 through the open end of said preheater.

This air mixes with the fuel vapor and steam leaving the pipe 18 where the same is entirely diffused by means of the baffles 22 so that when the fuel mixture leaves the nozzle 14 the same is in a highly combustible state. As soon as the fuel strikes the de-

flector 57 the same is thrown outwardly in fan shaped formation providing an outwardly flaring flame which strikes the walls of the boiler and follows along the same to the heating surfaces of the boiler situated above the fire pot. At the same time heat from the flame heats the coil 16 and the preheater 15 causing the same to provide additional steam and heated air for operating the burner. When it is desired to reduce the volume of heat from the burner the two valves 44 and 54 are simultaneously operated by the lever 55. The burner may thus be made to operate with a smaller flame than under normal conditions which is effected by adjusting the two valves 44 and 54 so that the same function properly under maximum and minimum requirements. If desired, a suitable heat regulator may be connected to the lever 55 for automatically operating the same. Such structure being well known in the art, has not been disclosed in detail in this application.

To permit of drawing the water from the generator 16 when the boiler or furnace is not in use, a pet cock 70 is employed which is inserted in the pipe 53, between said generator 16 and the valve 54. In the event that the burner goes out and fuel continues to flow from the pipe 18 and into the pipe 17 a safety device is provided which consists of a trap 71 connected to the elbow 40. When a sufficient head of liquid fuel is acquired the said trap opens and operates a suitable bucket mechanism for closing the fuel pipe emergency valve, not shown in the drawings. Such construction being well known in the art has not been illustrated in this application.

The advantages of my invention are manifest. An extremely simple and effective oil burner is provided in which the oil is not only heated prior to vaporization by the current of air injected into the burner nozzle, but also by the steam pipe conducting the live steam to the same. In this manner the fuel upon reaching the burner nozzle is easily vaporized so that a highly combustible fuel mixture is obtained upon leaving the burner. Due to the baffles within the nozzle the fuel mixture is completely diffused so that a uniform and even flame results with a minimum amount of noise. The flame is directed into the fire pot in such an angle that the same strikes the heating surface of the interior of the boiler and so that a portion of the heat is deflected to heat the preheater and steam generator connected with the burner. The preheater is so constructed that the same may be made to fit any of the usual sizes of boilers or furnaces now in common use for residences, so that but a single set of castings need be employed for any type of heating plant. By means of two unions the entire steam

coil may be removed from the burner for the purpose of repair or inspection when the occasion demands it. The burner may be readily constructed to fit any type of boiler or furnace.

5 Changes in the specific form of my invention, as herein disclosed, may be made within the scope of what is claimed without departing from the spirit of my invention.

10 Having described my invention, what I claim as new and desire to protect by Letters Patent is:

11 1. In combination, an oil burner comprising a conical plate disposed with its vertex lowermost and having a horizontal flared rim at the upper portion thereof, a nozzle extending centrally upwardly through the vertex of said conical plate, a toroidal air heater disposed above said horizontal rim, 20 a conical steam generator disposed above said conical plate with its vertex lowermost and spaced therefrom, said air heater and steam generator being concentrically arranged relative to said nozzle and connected therewith, a water pipe connected to said generator and a fuel pipe connected to said nozzle.

21 2. In combination, an oil burner comprising a centrally disposed nozzle, said nozzle having a deflector adapted to direct the flame 30 in an outward and upward direction to produce a conical flame formation, an air preheater and a steam generator disposed below said conical flame and adapted to receive the heat from below said flame, pipes 35 connecting said air preheater and steam generator with said nozzle, and a fuel pipe connected with said nozzle.

22 3. An oil burner for use within a heater, a horizontal partition extending across the 40 fire pot of said heater, a nozzle extending through said partition and above the same, and a steam generator and an air preheater lying immediately above said partition and adapted to receive the heat projected downwardly from the flame from said nozzle.

23 4. An oil burner comprising a nozzle centrally positioned within the fire pot of a heater and adapted to direct a flame laterally therefrom, an air preheater positioned 50 within the fire pot and near the wall thereof and encircling said nozzle, a steam generator coil positioned between said preheater and nozzle and encircling said nozzle, said steam generator and preheater being disposed to be successively subjected to the flame issuing from said nozzle, means for furnishing fuel oil to said nozzle, means for conducting steam from said steam generator coil to said nozzle, and means for conducting heated air from said preheater to said nozzle.

24 5. An oil burner for use within a heater having a circular fire pot comprising a toroidal air preheater positioned within the fire 60 pot and along the interior surface thereof,

a spiral steam generator encircled by said preheater and having the convolutions thereof arranged in conical formation with the apex thereof lowermost, a nozzle centrally positioned with respect to said fire pot, preheater and steam generator terminating above the lower convolution of said generator, said nozzle having a deflector for deflecting the burning gases issuing therefrom upwardly in a flaring manner along said steam generator and preheater, means for supplying liquid fuel to said nozzle, means for conducting steam for said steam generator coil to said nozzle, and means for conducting heated air from said preheater to said nozzle.

25 6. An oil burner for use within a heater comprising an air preheater and a steam generator jointly arranged to have the upper surfaces thereof disposed in substantially conical formation with the vertex of said joint structure lowermost, a nozzle centrally positioned with respect to said preheater and steam generator, and means for causing the flame issuing therefrom to be projected laterally in outwardly flaring relation to play upon the upper surfaces of said steam coil and preheater.

In testimony whereof I affix my signature.

HENRY DITTES.
